DESIGN FOR A FUEL FILTER

Styles T. Howard, Jeffersonville, Ind.

Application April 24, 1941, Serial No. 100,607

Term of patent 3½ years

To all whom it may concern:

Be it known that I, Styles T. Howard, a citizen of the United States, stationed at Jeffersonville Quartermaster Depot, Jeffersonville, Indiana, residing at Jeffersonville, in the county of Clark and State of Indiana, have invented a new, original, and ornamental Design for a Fuel Filter, of which the following is a specification, reference being had to the accompanying drawing forming a part thereof.

Fig. 1 is a perspective view of the fuel filter, showing my new design and

Fig. 2 is a side elevational view.

I claim:

The ornamental design for a fuel filter, substantially as shown.

STYLES T. HOWARD.
